DESIGN FOR A GAME BOARD FOR PLAYING WITH CARDS

Thomas M. Anderson, Roscoe, Calif., assignor to
Ugca Game Company, Los Angeles, Calif., a co-
partnership consisting of Thomas M. Anderson
and David G. Watts

Application June 14, 1939, Serial No. 85,494

Term of patent 3½ years

To all whom it may concern:

Be it known that I, Thomas M. Anderson, a citizen of the United States, residing at Roscoe, in the county of Los Angeles and State of California, have invented a new, original, and ornamental Design for a Game Board for Playing with Cards, of which the following is a specification, reference being had to the accompanying drawing, forming part thereof.

The figure is a plan view of a game board for

playing with cards, a portion being broken away for convenience of illustration, showing my new design.

The article is of no appreciable thickness and the features are flush with the surface.

I claim:

The ornamental design for a game board for playing with cards, as shown and described.

THOMAS M. ANDERSON.
